(57) **CLAIM**

The ornamental design for a suitcase insert, as shown and described.

DESCRIPTION

FIG. 1 is a perspective view of the suitcase insert showing my new design, shown without lid for clarity of disclosure;

FIG. 2 is a left side view thereof;

FIG. 3 is a right side view thereof;

FIG. 4 is a front view thereof;

FIG. 5 is a back view thereof;

FIG. 6 is a top view thereof;

FIG. 7 is a bottom view thereof;

FIG. 8 is a top view thereof with lid;

FIG. 9 is a perspective view of the suitcase insert in use within a suitcase without lid for clarity of disclosure; and,

FIG. 10 is the cross sectional view taken in the direction of lines 10-10 of FIG. 6.

The appearance of separation, break lines, and brackets shown in FIGS. 1-5, 8, and 10, form no part of the claimed design except for indicating indeterminate depth.

The broken lines are for illustrative purposes only and form no part of the claimed design.
